US0D1091558S

(12) **United States Design Patent** (10) **Patent No.:** **US D1,091,558 S**
(45) **Date of Patent:** **** Sep. 2, 2025**

(54) **MOUNT HEAD AND MONITOR ARM
INCLUDING THE SAME**

(71) Applicant: **Humanscale Corporation**, New York, NY (US)

(72) Inventors: **Fabian Monsalve**, New York, NY (US); **Ross Velazquez**, New York, NY (US); **Jacob Glickstein**, Golden Valley, MN (US)

(73) Assignee: **Humanscale Corporation**, New York, NY (US)

(**) Term: **15 Years**

(21) Appl. No.: **29/968,643**

(22) Filed: **Oct. 17, 2024**

(57) **CLAIM**

The ornamental design for a mount head and monitor arm including the same as shown and described.

DESCRIPTION

FIG. 1 is a left, rear perspective view of a mount head and monitor arm including the same showing the design; FIG. 2 is another left, rear perspective view of the mount head of the mount head and monitor arm including the same; FIG. 3 is a right, front perspective view of the mount head of the mount head and monitor arm including the same; FIG. 4 is a front view of the mount head of the mount head and monitor arm including the same; FIG. 5 is a rear view of the mount head of the mount head and monitor arm including the same; FIG. 6 is a left side view of the mount head of the mount head and monitor arm including the same; FIG. 7 is a top view of the mount head of the mount head and monitor arm including the same; and, FIG. 8 is a bottom view of the mount head of the mount head and monitor arm including the same. The broken lines in FIGS. 1-8 illustrate portions of the mount head and monitor arm including the same that form no part of the claimed design.

1 Claim, 8 Drawing Sheets
